UNITED STATES PATENT OFFICE.

EDGAR H. FREEMAN, OF TRENTON, NEW JERSEY, ASSIGNOR TO E. H. FREEMAN ELECTRIC COMPANY, OF TRENTON, NEW JERSEY, A CORPORATION OF NEW JERSEY.

ELECTRICAL SIGN-RECEPTACLE.

1,079,483.

Specification of Letters Patent. Patented Nov. 25, 1913.

Application filed May 17, 1913. Serial No. 768,235.

To all whom it may concern:

Be it known that I, EDGAR H. FREEMAN, a citizen of the United States, residing at Trenton, in the county of Mercer and State 5 of New Jersey, have invented certain new and useful Improvements in Electrical Sign-Receptacles, of which the following is a specification.

This invention relates to electrical receptacles of the type which are specially adapted for use as sign receptacles to carry the lamps of an electric sign.

The principal object of the invention is to provide an electrical sign receptacle of 15 simple and compact construction, and one in which the active parts of the receptacle are thoroughly and effectually protected from weather conditions. At the same time the invention contemplates a construction 20 of receptacle which embodies a minimum number of parts of simple and practical design so that the same can be easily and cheaply manufactured, while at the same time arranged in such a manner as to insure 25 the establishment and maintenance of an electrical circuit when the two parts of the receptacle are secured together so as to engage respectively upon opposite sides of a supporting element or sign sheet.

Another general object of the invention 30 is to preserve therein the desirable feature of having the two principal parts or members of the receptacle act as a clamp for engagement with the sign sheet so that other 35 supporting or fastening means are unnecessary to secure the receptacle to the sheet.

With these and other objects in view, the invention consists in certain novel combinations and arrangements of the parts as will 40 more fully appear as the description proceeds, the novel features thereof being pointed out in the appended claims.

For a full understanding of the invention, reference is to be had to the following 45 description and accompanying drawings, in which—

Figure 1 is a front view of an electrical sign receptacle embodying the present invention, showing the sign sheet in dotted

lines. Fig. 2 is a rear elevation of the same. 50 Fig. 3 is an enlarged sectional view of the complete receptacle shown clamped in position on a sign sheet or equivalent supporting element. Fig. 4 is a detail view in perspective of the inner porcelain cup member 55 of the receptacle. Fig. 5 is a perspective view, parts broken away, of the outer porcelain cup member of the receptacle.

Like reference characters designate corresponding parts in the several figures of 60 the drawings.

The improved receptacle includes in its general organization two principal parts or members, namely an inner cup member 1 and an outer cup member 2 adapted to be 65 fitted one within the other and also adapted to be clamped respectively upon opposite sides of the sign sheet or other supporting element S, said supporting element being provided with the usual hole or opening 70 through which the receptacle body is inserted and exposed for the mounting of the electrical plug carried by the lamp.

The telescopically registering cup members 2 and 3 are made of porcelain, fiber, or 75 other insulating material such as is commonly employed for manufacturing fixtures of this character, and for the purpose of properly securing the receptacle within the sign sheet and to prevent turning thereof, 80 the sign sheet preferably has the opposite edge portions of its opening, as at 3, pressed by retaining projections 4, on the inner cup member 1, into keeper notches 5 formed at opposite points in the clamping edge portion 85 of the outer cup member 2. The said clamping edge portion of the outer cup member 2 clamps against one side of the sign sheet, and the shouldered collar 6 at the outer edge of the inner cup member 1 90 clamps upon the opposite side of the sign sheet, as shown, thus providing a self-sustaining clamp for the receptacle which is also held against turning.

According to the present invention, the 95 inner cup member 1 is adapted to loosely register within the socket of the outer cup member 2, and is provided with an integral

insulating bottom piece 7 which is of a solid formation and provides a substantial base upon which is secured the screw shell contact 8 which is housed entirely within the 5 socket part of the said inner cup member. The screw shell or side contact 8 is provided at its inner edge with an inturned securing flange 9 that rests flat upon the bottom piece 7 and is held in place by the combined 10 conducting and securing screws 10 which pass through screw openings 11 provided therefor in the said bottom piece 7. The threaded ends of the said screws 10 engage in threaded openings formed in opposite 15 portions of a universal contact ring 12 arranged flat against the outer side of the bottom piece 7, so as to be housed wholly within the space between the said bottom piece and the inner side of the integral insulating bottom piece 13 of the outer cup member 2.

The center plug contact of the receptacle consists of a single connecting screw 14 extending through aligned central openings 25 provided respectively in the bottom pieces 7 and 13, and the head of the said screw is exposed centrally at the bottom of the plug-receiving opening or socket within the inner cup member 1 so as to make contact 30 with the center contact of the electrical plug. The threaded portion of the combined center plug contact and the connecting screw 14 projects through the center opening in the bottom piece 13 of the outer cup member 35 and engages a threaded opening 15 in one end of a wire terminal plate 16, which is held seated within a plate recess 17 by means of a suitable securing screw 18. The said recess 17 is formed in the outer side of the 40 bottom piece 13 of the outer cup member, and carries the usual binding screw 19 which is exposed in the plane of one of the line wire grooves 20.

The through line wire groove 20^a formed 45 in the outer side of the bottom piece 13 has exposed therein a through wire terminal plate 21 which carries a binding screw 22 and is of a forked construction so as to provide oppositely extending arms 23, one terminal of each of said arms being threaded to receive the threaded end of a conducting screw 24 extending through the bottom piece 13 and also through one arm of a folded or doubled contact spring 25 seated in a recess 50 26 in the inner side of the bottom piece 13. Thus, a pair of the contact springs 25 is held at the inner side of the bottom piece 13 and housed in the space between the two bottom pieces 7 and 13 for substantial engagement with the universal contact ring 12. Accordingly, regardless of the relative rotation of the two cup members, the springs 25 and the contact ring 12 insure a positive 55 electrical contact between the screw shell

contact and one of the wire terminal plates, 65 and furthermore the springs 25 adapt themselves, within reasonable limits, to the relative longitudinal or telescopic adjustment of the two cup members. Consequently, this provides a means for establishing and maintaining electrical communication between the plug contacts and the wire terminal plates under all reasonable adjustments of the receptacle, while at the same time thoroughly protecting the interior contacts from 75 outside weather conditions and only leaving exposed the binding connections for the line wires.

From the foregoing, it is thought that the construction, operation, and many advantages of the herein-described electrical sign receptacle will be readily apparent without further description, and it will be also understood that changes in the form, proportion, and minor details of construction may 85 be resorted to without departing from the spirit or sacrificing any of the advantages of the invention.

What I claim is:

1. A sign receptacle comprising a pair of 90 telescoping cup members, wire terminal plates arranged upon one of the cup members, plug contacts carried by the other cup member, one of said plug contacts having a direct connection with one of the wire terminal plates, a contact member carried by one of said cup members adapted to be housed in the space between the said two cup members, and contact springs carried by the other of said cup members also adapted to be 100 housed within the space between the two cup members for engagement with said contact member; said contact springs having electrical connection with the other wire terminal plate.

2. A sign receptacle comprising a pair of telescoping cup members, one of which carries both wire terminal plates, a combined center plug contact and connecting screw adjustably connected with one wire terminal 110 plate, a screw shell contact arranged within one cup member, a contact ring connected with the screw shell contact and arranged upon the outside face of the bottom piece of one cup member, and contact springs fitted upon the inner face of the bottom piece of the other cup member and connected with the other wire terminal plate, said springs being adapted to metallically engage with said contact ring when the two members are 115 120 united.

3. A sign receptacle comprising a pair of telescoping cup members, two wire terminal plates mounted upon the outer side of the bottom of the outer cup member, one 125 of said wire terminal plates being of a forked construction, a pair of contact springs fitted to the inner face of said bottom piece

of the cup member and having screw connections respectively with the separate arms of the forked wire terminal plate, a center plug contact screw extending through the bottoms of both cup members and engaging one wire terminal plate, a screw shell contact within the inner cup member, and a contact ring having screw connections with the shell contact and mounted upon the

outer face of the bottom of the inner cup 10 member.

In testimony whereof I hereunto affix my signature in the presence of two witnesses.

EDGAR H. FREEMAN.
